(57) **CLAIM**

The ornamental design for a sample container for plasma spectroscopic analyzer, as shown and described.

DESCRIPTION

FIG. 1 is a rear view of a sample container for plasma spectroscopic analyzer showing my new design;

FIG. 2 is a front view thereof;

FIG. 3 is a left side view thereof;

FIG. 4 is a right side view thereof;

FIG. 5 is a front top perspective view thereof; and,

FIG. 6 is a rear bottom perspective view thereof.
